UNITED STATES PATENT OFFICE.

FREDERICK C. SHAFER, OF GRAND RAPIDS, MICHIGAN, ASSIGNOR TO KEELER BRASS COMPANY, OF GRAND RAPIDS, MICHIGAN, A CORPORATION OF MICHIGAN.

COMBINED LOCK AND LATCH.

1,152,124.

Specification of Letters Patent. Patented Aug. 31, 1915.

Application filed June 29, 1914. Serial No. 847,838.

To all whom it may concern:

Be it known that I, FREDERICK C. SHAFER, a citizen of the United States of America, residing at Grand Rapids, in the county of 5 Kent and State of Michigan, have invented certain new and useful Improvements in Combined Locks and Latches; and I do hereby declare the following to be a full, clear, and exact description of the invention, 10 such as will enable others skilled in the art to which it appertains to make and use the same.

My invention relates to a combined lock and latch, and more particularly to such 15 devices adapted for use on refrigerators or similar structures, and its object is to provide a latch that will automatically force a door to a tightly closed position, and a lock co-acting therewith to secure the latch 20 and prevent opening the door, and to provide the device with various new and useful features as hereinafter more fully described and particularly pointed out in the claims, 25 reference being had to the accompanying drawings, in which:—

Figure 1 is a side elevation of a device embodying my invention; Fig. 2 a front elevation of the same; Fig. 3 a detail of the detachable inner plate of the housing; Fig. 4 30 an elevation of the inner side of the device with said plate removed; Fig. 5 a vertical section through the lock; and Fig. 6 a vertical section through the latch on the line 35 *a—b* of Fig. 2.

Like numbers refer to like parts in all of the figures.

1 represents a portion of the casing of a refrigerator or other like structure; 2 a portion of the door of the same which overlaps the casing and is held tightly against the same by means of the latch.

3 represents the housing of the device adapted to be secured to the outer surface of the door 2.

4 is an outwardly projecting lug on the margin of the housing adjacent the edge of the door.

5 is a lever pivoted to the lug 4 and serving as a handle to manually release the latch 50 and to open the door.

6 is an inwardly projecting arm integral with the lever 5, extending within the housing through an opening therein and engaging the upper wall of said opening to limit the inward movement of the lever 5.

7 is a latch member projecting laterally from the side of the lever 5 near the pivot thereof and adapted to pass under a keeper 8 as the lever is swung outward, and to engage an inclined cam surface 9 on the keeper to force the door into close contact with the casing.

An oppositely inclined surface 10 is provided on the keeper which when the door is being closed engages the latch member 7 65 and forces the same downward and the lever 5 outward until the member 7 passes the angle of this keeper.

To automatically force the door in close contact with the casing a spring 11 within 70 the housing engages the under side of the arm 6 and yieldingly forces the same upward along the inwardly inclined surface 9 and wedges the door tightly against the casing 1.

To lock this latch in closing position the arm 6 is provided with a recess 6^a and a locking plate 12 is provided having a projection 21 adapted to enter this recess and hold the arm from moving downward, thus preventing the latch from being released. This plate carries this projection near one end and at the other end is pivoted on a screw 17 inserted in the back of the housing, which also retains the plate 13 which closes the side 85 of the housing adjacent the door. This plate is held in place by a hook 20 at one end and by the screw 17 at the other end. The locking plate 12 is provided with a central opening 22 having parallel sides adapted to be engaged by a flat key 19 to shift the plate into locking and unlocking position. This key is inserted in a rotative pin 18 having a slot therein to receive the key, this pin being journaled in the housing at one end and in the closing plate 13 at the other end.

To prevent the locking plate from shifting, the movable end of the same is provided with a projection 15 which slides over an opposing projection 16 on the closing plate 100 13 and is yieldably held against the said projection by a spring 14 which spring yields to permit the projection 15 to pass the projection 16 as the locking plate is moved by the key to engaging or disengaging position. 105

What I claim is:—

1. In a device of the class described, a housing, an outwardly projecting lug on the housing, a lever pivoted to the lug, an arm on the lever extending within the housing, a 110

latch member extending laterally from the lever near the pivot thereof, a keeper having an inwardly inclined cam surface slidably engaged by the latch member, and a spring in the housing engaging the said arm to force the latch member into said engagement and to wedge the door to closed position.

2. In a device of the class described, a housing adapted to be attached to a door, a lug projecting outward from the housing near one side thereof, a lever pivoted to the lug and having an arm extending through an opening in the housing and provided with a recess, a spring in the housing engaging said arm, a pivoted locking plate in the housing and having a projection to engage the recess and an oblong opening, a pin rotative in said opening in the plate and provided with a slot to receive a key to shift the plate.

3. In a device of the class described, a pivoted lever, an arm and a latch member projecting from the lever, a keeper having an inclined surface slidably engaged by the latch member to force a door to closed position, and a spring engaging the arm to yieldably force the latch member into said engagement with the keeper.

4. In a device of the class described, a lever pivoted to swing downward, a latch member projecting laterally from the lever, an arm projecting inward from the lever, a keeper having oppositely inclined lower

surfaces slidably engaged by the latch member, and a spring engaging the under side of the arm to yieldably force the latch member in contact with said surfaces.

5. In a device of the class described, a housing, a lever pivoted on the housing, an arm on the lever projecting into the housing, a stop on the housing to engage the arm and limit the upward movement of the same, a spring engaging the arm oppositely to the stop, a latch member projecting laterally from the lever, and a keeper having an oppositely inclined under side slidably engaged by said latch member.

6. In a device of the class described, a lever pivoted to swing downward, a laterally projecting latch member on the lever, a keeper engaged by the said member, an inwardly projecting arm on the lever, a spring engaging the arm to swing the lever upward, a stop opposite the spring to limit the upward movement of the arm, a pivoted plate having a projection to engage and hold the arm, and an elongated central opening and a rotative pin in said opening, provided with a stop to receive a key.

In testimony whereof I affix my signature in presence of two witnesses.

FREDERICK C. SHAFER.
